(57) **CLAIM**

The ornamental design for a bracket for face shield, as shown and described.

DESCRIPTION

FIG. 1 is a perspective view of the bracket for face shield according to the invention;

FIG. 2 is a front view thereof;

FIG. 3 is a rear view thereof;

FIG. 4 is a left-side view thereof, the right-side view being a mirror image thereof;

FIG. 5 is a top view thereof; and,

FIG. 6 is a bottom view thereof.

The broken lines shown in the drawing represent the safety helmet and the face shield that form no part of the claimed design.
